UNITED STATES PATENT OFFICE.

ALEXANDER KISH, OF NORTH ADAMS, MASSACHUSETTS.

LAWN SWING.

Application filed December 13, 1923. Serial No. 620,520.

To all whom it may concern:

Be it known that I, ALEXANDER KISH, a citizen of Rumania, residing at North Adams, in the county of Berkshire and State of Massachusetts, have invented a new and useful Lawn Swing, of which the following is a specification.

The object of my invention is to provide a lawn swing of novel construction, the base and seat of which maintain a horizontal position throughout its swinging movement; to provide a swing having novel means for lowering the backs of the swing seats whereby they may be used for reclining; to provide a table in such a swing; to provide canopies for the swing including novel means for extending same; and to provide the novel combination and arrangement of parts disclosed in the following specification and the accompanying drawings, in which—

Figure 1 is a side elevation of my invention with portions of members 3 broken away;

Fig. 2 is a vertical transverse section through the center of the swing;

Fig. 3 is a longitudinal section on line 3—3 of Fig. 2;

Fig. 4 is a detail horizontal section on line 4—4 of Fig. 2; and

Fig. 5 is a diagrammatic view of the seat back and means for lowering same, the dotted line showing the relation of the parts while the seat is in the process of being lowered.

Like numerals designate like parts in each of the several views.

Referring to the accompanying drawings, I provide a conventional outside frame 1 having cross rods 2 from which are pivotally suspended the swing arms 3 by means of metal straps 4. On the lower end of arms 3 are metal straps 6 which pivotally engage the cross bars 7 of the bottom frame 5. Affixed to the central portion of frame 5, on opposite sides thereof, are vertical standards 8 connected by a table 9 and by a tiltable or swingable foot rest 10, mounted on pivots 11. I provide a foot rest 12 which is independent of bottom frame 5, said foot rest 12 being suspended by hook bars 13 by hook ends 14 which hook over the cross bars 15 attached to arms 3, as shown in Fig. 3.

I provide upright side members 16 affixed to bottom frame 5 and carrying the curved seats 17 to which the seat backs 18 are ad-

justably attached on pivot rods 19. I further provide arms 20 pivotally attached to seat backs 18, as shown in Figs. 1 and 2. I provide links 22 attached by pivot 23 to arms 20 and by pivots 24 to side members 16 to permit of lowering of the seat backs. I provide suitable spring controlled canopy rollers or curtains 26 on the upper end of standards 8, the canopy 26 being attached to the upper ends 27 of seat backs 18, as shown in Fig. 3. I provide a suitable metal canopy 28 as shown in Figs 2 and 3, extending over rollers 25 and serving to protect the canopies from the weather.

In operating this swing the bottom frame 5, seats 17, and foot rest 12, all being pivotally or swingably supported, maintain a horizontal position throughout the swinging movement of swing arms 3. Side members 16 are affixed to bottom frame 5 but are pivotally connected by link 22 to the arms 20, which in turn are pivotally connected to seat backs 18 and disconnected from standards 8, permitting of a movement which maintains the seat chairs 17 in a horizontal position.

In order that the swing may be used for reclining, the seat backs 18 may be lowered to a nearly horizontal position by moving members 20 and 22 upward and rearward in the manner illustrated by the dotted lines and arrows designated 29 and 30 in the diagrammatic view, Fig. 5.

When the seat backs 18 are shifted to a lowered or horizontal position they hold down the canopy 26, which is mounted on the spring controlled roller 25 in a manner similar to that of the conventional window shade, thereby providing complete protection for the occupants of the swing at all times. The metal canopy 28 protects the spring rollers from rain and thus from rusting. Table 9 maintains a horizontal position as it is mounted on standards 8, which are affixed to bottom frame 5, which latter frame is always horizontal, owing to its pivotal connection with the bottom ends of the swing arms 3. The small foot rest 10 is pivotally supported on standards 8 and may be tilted to either a vertical position, as shown in Fig. 3, or to a horizontal position, as shown in Fig. 1.

Seat bottoms 17 are rigidly mounted on side members 16 which in turn are affixed to bottom frame 5 and keep a horizontal position along with that frame, due to its piv-

otal connection to swing arms 3, by straps 6 and cross rod 7.

What I claim is:

1. In a lawn swing, the combination of a supporting frame having cross rods, arms swingably suspended from the cross rods, a bottom frame pivotally suspended from the lower ends of the swing arms, a swing propulsion foot rest swivelly suspended from the swing arms and independent of the bottom frame, upright side members affixed to the bottom frame, seats affixed to the side members, vertical standards affixed to the bottom frame midway between the seats, and a table affixed to the said standards, whereby the seats and table will maintain a horizontal position throughout the swinging movement of the swing.

2. In combination with the apparatus described in claim 1, seat backs pivotally attached to the seats, arms pivoted to the seat backs, and links pivotally connecting the said arms with the side members, said links being of such length as to permit of lowering the seat backs to an approximately horizontal position to permit of reclining in the swing.

3. In combination with the apparatus described in claim 1, seat backs pivotally attached to the seats, flexible waterproof canopies attached to the seat backs, spring controlled rollers on which said canopies are mounted, said rollers being supported from the vertical standards.

4. In combination with the apparatus described in claim 1, seat backs pivotally attached to the seats, flexible waterproof canopies attached to the seat backs, spring controlled rollers on which said canopies are

mounted, said rollers being supported from the vertical standards, and a metal canopy mounted on the vertical standards and extending over the spring controlled rollers to protect the mechanism of said rollers from water.

5. In a lawn swing, the combination of a supporting frame having cross rods, a plurality of pairs of swing arms, metal straps attached to the ends of said swing arms, the upper straps engaging over the cross rods, a bottom frame having cross rods pivotally supported by the metal straps on the lower ends of the swing arms, a swing propulsion foot rest, a wire frame supporting said foot rest, said wire frame having hook ends, cross rods extending between the swing arms on which said hook ends are swivelly hung, upright seat supporting side members attached to the bottom frame, seats affixed to the said side members, backs pivotally mounted on the seats to permit of lowering same, arms pivoted to the backs at one end and free at the other end, links pivotally connecting the said arms with the rigid side members which carry the seats whereby the said arms may be swung to either a position in which the seat back is lowered or to a position in which it is maintained in a slightly inclined position.

6. In combination with the apparatus described in claim 5, the combination of flexible canopies attached to the seat back, means permitting of unrolling the said canopies when the seat backs are lowered, and a metal canopy over the rolled up portion of the flexible canopies.

ALEXANDER KISH
